UNITED STATES PATENT OFFICE

THORE R. E. RUNDQVIST, OF CLAREMONT, NEW HAMPSHIRE, ASSIGNOR TO SULLIVAN MACHINERY COMPANY, A CORPORATION OF MASSACHUSETTS

DRILLING MECHANISM

Application filed June 10, 1925. Serial No. 36,261.

My invention relates to drilling mechanisms.

In drilling, especially in nitrate or other similar material, it is desirable to drill holes of comparatively large diameter and of moderate depth. To accomplish this it has heretofore been necessary to utilize a drill mounting having relatively high upstanding supports or guides for the drilling mechanism and it has been found that such an arrangement is bulky and somewhat top heavy especially during transport of the drill up or down steep inclines or over rugged surfaces.

15 Among the objects of the present invention are the provision of means for swinging the guiding frame for the drilling mechanism downwardly, thus lowering the center of gravity of the drill during transport.

20 Another object of my invention is to provide an improved drilling mechanism having improved feeding and drill actuating connections. Still another object of my invention is to provide an improved drilling mecha-

25 nism having the drill guiding frame pivoted for angular adjustment relative to the supporting frame and which has improved feeding and drill actuating connections which are operative irrespective of the angular ad- 30 justed position of the guiding frame. A still further object of my invention is to pro- 35 vide an improved drilling mechanism having improved independent rotation means for the drill bit. These and other objects and advantages of my invention will, however, hereinafter more fully appear.

My invention, in one of its aspects, comprises improved means for angularly adjusting a drill guiding frame relative to a sup- 40 porting frame while constantly maintaining operative driving connections for the feeding and drill actuating mechanism. More specifically, this improved means comprises a supporting frame of the track-laying tread driven type by which a power unit is carried and on which a drill guiding frame is piv- 45 ily connected for angular adjustment relative thereto. The feeding means for the drill comprises a usual tractor pulley which 50 is operatively connected to a driven pulley,

the latter being mounted concentric with the pivotal axis of the guiding frame. The guiding frame or standard comprises a plurality of columns, herein in the form of feed screws, rigidly connected together at their ends and by which the drill bit actuating mechanism is carried. Transmission shafts are arranged parallel to the feed screw columns and are operatively connected to the source of power through suitable chain and gear connections of improved form. During transport the guiding frame is adapted to be swung downwardly, thus forming a low and compact unit having a relatively low center of gravity, consequently facilitating the transport of the machine over inclined or rugged surfaces. When it is desired to operate the drill the guiding frame may be swung upwardly with facility into its operative position and rigidly locked therein.

In the accompanying drawings I have shown for purposes of illustration one form which my invention may assume in practice.

In these drawings,—

Fig. 1 is a side elevation of my improved drilling mechanism with the drill standard disposed in its lowered position, the elevated position of this standard being indicated by dotted lines with the drill actuating mechanism shown in raised position.

Fig. 2 is a detail central longitudinal sectional view illustrating a portion of my improved feeding mechanism, the view being taken substantially on line 2—2 of Fig. 6.

Fig. 3 is an enlarged detail elevational view, partially shown in section, of a portion of my improved feeding and drill actuating mechanism.

Fig. 4 is a transverse horizontal sectional view taken substantially on line 4—4 of Fig. 3 illustrating a portion of my improved independent drill bit rotation means.

Fig. 5 is a fragmentary elevational view of the improved means for preventing reciprocation of the drill bit during rotation thereof.

Fig. 6 is a transverse horizontal sectional view taken substantially on line 6—6 of Fig. 3.

Fig. 7 is a transverse horizontal sectional

view taken substantially on line 7—7 of Fig. 3.

Fig. 8 is a detail sectional view of the improved raising and lowering means for the 5 drill guiding frame, the view being taken substantially on line 8—8 of Fig. 3.

Fig. 9 is a detail central longitudinal sectional view taken substantially on line 9—9 of Fig. 6.

10 Fig. 10 is a plan view of the drilling mechanism shown in Fig. 1, parts being broken away and omitted to facilitate illustration.

In this illustrative embodiment of my invention I have shown a truck frame 1 supported on usual track-laying treads 2 and by which a power unit 3 is supported. A usual driving pulley 4 projects laterally from the side of the power unit and is adapted to be actuated by the latter in a well known manner. The track-laying treads are adapted to be driven from the power unit 3 through any suitable connections including flexible drive chains 5. As illustrated, mounted upon the truck frame 1 is a pair of parallel I-beams 6 rigidly secured to the truck frame in any suitable manner and upon which the power unit 3 may be supported at their forward ends.

In my improved construction I have provided a supplemental or drill guiding frame or standard, generally designated 7, pivotally connected to the truck frame 1, as at 8, for angular adjustment relative thereto. More specifically, this drill guiding frame comprises a yoke-shaped hollow base casting 9 having laterally projecting cylindrical trunnions 10 journaled within suitable bearing blocks 11 rigidly secured to the upper surfaces of the I-beams 6. It will herein be observed that formed on the base casting 9 are laterally projecting lugs 12 which are adapted to rest on and to be secured to the I-beams 6. Suitable upstanding bosses 13 are also formed integral with the base casting 9 and within which stationary feed screws 14 and 15 are secured herein by thread and bolt connections 16 and 17, respectively. The upper ends of the feed screw columns 14 and 15 are rigidly secured, as by key and nut connections 18, within a yoke-shaped top casting 19. The drill actuating mechanism is supported upon the feed screw columns in an improved manner to be hereinafter more fully described.

55 Improved means are provided for angularly adjusting the drill guiding frame 7 relative to the truck frame 1 and which comprises a worm gear or rack 20 rigidly secured, as by bolts 21, to a radial flange 22 preferably formed integral with one of the trunnions 10 for the drill guiding frame 7. As illustrated, a worm 23 is meshed with the worm gear 20 and this worm is suitably secured to a vertically disposed shaft 24 journaled at its upper and lower ends, preferably in ball bear-

ings 25 and 26, respectively (see Figs. 3 and 8). Suitably secured to the upper end of the shaft 24 is a worm gear 27 with which a worm 28 is meshed and which worm is secured to a transversely disposed horizontal shaft 29. Suitably secured to the outer end of the shaft 29 is an operating lever or crank 30. It will herein be noted that the gearing above described is suitably housed within a dust tight casing 31 herein preferably formed integral with one of the bearing blocks 11. From the foregoing description it will be evident that when the operating member 30 is actuated by the operator, and consequently the gears 28, 27, 23, 80 and 20, the drill guiding frame may be swung in any desired manner about its pivotal axis 8 relative to the truck frame 1.

In specifically describing my improved drill actuating mechanism it will herein be observed that power is adapted to be transmitted from the tractor driving pulley 4 through a belt connection 35 to a larger driven pulley 36 mounted concentrically with the trunnion pivot 8 and which pulley is suitably secured to a transversely disposed horizontal transmission shaft 37 suitably journaled at its ends, preferably in ball bearings, as at 38 and 39, herein suitably carried within the hollow base frame 9. Operatively connected to the inner end of the shaft 37 is a chain sprocket 40 from which power is transmittable through a chain connection 41 to a similar chain sprocket 42 suitably secured to a shaft 43 disposed parallel with the shaft 37 and the trunnion pivot 8, which shaft 43 is suitably journaled in ball bearings 44 carried within the base casting (see Figs. 6 and 9). Suitably secured at the inner end of the shaft 43 is a bevel pinion 45 which is herein meshed with reverse bevels 46 and 47 loosely journaled on a transmission shaft 48 disposed parallel with the feed screw columns 14 and 15. It will herein be noted that the shaft 48 is journaled in any suitable manner at its lower and upper ends within the lower and upper castings 9 and 19, respectively. As shown, disposed coaxially with the shaft 48 and interposed between the reverse bevels 46 and 47 is a suitable friction clutch, generally designated 49, by which the reverse bevels 46 and 47 are adapted to be selectively connected in operative driving relation with the shaft 48 to drive the latter in opposite directions from the bevel drive pinion 45. Any approved means including an operating member 50 may be provided for actuating the friction clutch 49. As illustrated, splined, as at 51, in operative sliding relation with the shaft 48 and adapted to be driven thereby is a bevel pinion 52 which is meshed with a bevel gear 53 suitably keyed, as at 54, to one end of a horizontally disposed crank shaft 55. As illustrated, the crank shaft 55 is journaled at its ends within roller 130

bearings 56 carried, respectively, within a suitable detachable cover or cap member 57 and the main drill casting or frame, generally designated 58, and by which the drill bit 5 actuating mechanism per se is carried in an improved manner. Suitably secured to the end of the crank shaft 55 opposite from the gear 53 is a balancing or fly-wheel 59. It will herein be observed that a yoke-shaped 10 connecting rod 60 is pivotally connected as at 61 and 62, respectively, to the crank shaft 55 and to the drill actuating and pressure generating cylinder, generally designated 63. As this cylinder 63 and associated mechanism 15 does not specifically enter into my invention and is the invention of one Henry H. Mercer and disclosed by him in a pending application, Ser. No. 472,546, filed May 25, 1921, further detailed discussion of the same is believed unnecessary other than to say that a 20 drill bit carrying drill rod 64 is operatively connected to a piston 63^a reciprocating in the cylinder and is adapted to be reciprocated thereby. The piston rod is hollow as indicated in dotted lines and has an extension 64^a 25 cooperating with a sleeve 64^b for supplying fluid from a compartment 64^c for cleaning the cuttings from a drilled hole. The compartment 64^c is formed by the partition 64^d 30 in the cylinder. Cleansing fluid may be supplied to this compartment by any suitable means such as described in the application referred to above. The cylinder 63 is provided with integral rectangular guide portions 65 35 slidably mounted within a corresponding rectangular guiding portion 66 formed integral with the casting 58 (see Fig. 3). From the foregoing description it will be evident that when the gear 45 is being 40 driven and when one or the other of the reverse bevels 46 and 47 are selectively connected to the shaft 48, the crank shaft 55 and consequently the drill cylinder 63 may be actuated as desired. 45 Associated with my improved drill actuating mechanism is improved feeding means which specifically comprises a bevel gear 70 which is meshed with the reverse bevels 46 and 47 and driven thereby (see Fig. 6). The 50 gear 70 is suitably connected to the inner end of a transversely disposed shaft 71 disposed coaxially with the shaft 43 and which shaft 71 is journaled in a suitable roller bearing 71^a carried by the base frame 9. As illustrated, suitably secured to the outer end of the shaft 71 is a bevel pinion 72 which is meshed with reverse bevels 73 and 74 loosely journaled on a shaft 75 disposed transversely of the shaft 71 (see Figs. 2 and 6). 55 The opposite ends of the shaft 75 are journaled within suitable roller bearings 76 likewise carried within the base frame 9. Disposed coaxially with the shaft 75 and interposed between the reverse bevels 73 and 74 60 is a suitable friction clutch, generally designated 77, substantially similar to the friction clutch 49 heretofore described, and by which the gears 73 and 74 are adapted to be connected in driving relation with the shaft 75. The clutch 77 is adapted to be actuated 65 by a suitable shifter member 78 operated by an operating member or lever 79. As illustrated, secured to one end of the shaft 75 is a bevel pinion 80 (see Fig. 2) which is meshed with a bevel gear 81 keyed, as at 82, to the lower end of a transmission shaft 83 disposed parallel with the feed screw columns 14 and 15 and the transmission shaft 48. The lower end of the shaft 83 is journaled within suitable ball bearings 84 while the upper end of the shaft is suitably journaled within the upper yoke casting 19. Splined in sliding relation to the shaft 83, as at 85, is a spur pinion 86 (see Fig. 7) which is suitably journaled within the main casting 58 of the drilling mechanism per se. The gear 86 is meshed with a larger spur gear 87 (see Figs. 3 and 7) formed integral with a rotatable feed nut 88 threadedly connected, as at 89, to the stationary feed screw 14. It will herein be noted that carried within the casting 58 at the ends of the nut 88 are suitable ball thrust bearings 90 by which the thrust of the drill is taken. Formed integral with the nut 88 and above the gear 87 is a chain sprocket 91 which is 95 operatively connected by a transversely disposed chain connection 92 with a similar chain sprocket 93 formed integral with a rotatable feed nut 94, similar to the nut 88 and driven by the latter. The nut 94 is threadedly connected, as at 95, to the stationary feed screw 15. From the foregoing description it will be evident that when the bevel pinion 72 is being driven from the power unit 3 and when one or the other of the reverse bevels 73, 74 are operatively connected to the shaft 75 power may be transmitted through the bevels 80 and 81 and the shaft 83 to the feed nuts 88 and 94, rotating the latter relative to the stationary feed screws, thus causing the drill carrying frame 58 and consequently the bit carrying drill rod 64 to be fed upwardly or downwardly as desired. It will herein be noted that secured to the end of the shaft 75 opposite from the bevel pinion 80 is a hand wheel 96 (see Fig. 2), thus enabling the shaft 75 and consequently the feed nuts 88 and 94 to be manually rotated and consequently the drill manually fed as desired. 100 Associated with the improved drill actuating mechanism are improved means for independently rotating the drill rod 64 and this means specifically consists of a chain sprocket 100 suitably secured to the crank shaft 55 (see Fig. 7) intermediate the fly-wheel 59 and the adjacent side of the casing 58. This chain sprocket is operatively connected by means of a drive chain 101 (see Fig. 3) with a similar chain sprocket 102 (see also Fig. 4) 105 110 115 120 125 130

suitably secured to a transversely disposed shaft 103 journaled within suitable bearings 104 carried within a head or closure member 105, the latter being secured within the lower end of the rectangular guiding portion 66 of the frame casting 58. Suitably secured to the shaft 103 intermediate its ends is a worm 106 which is meshed with a worm gear 107 disposed coaxially with the drill rod 64 and splined in sliding relation with respect thereto, as at 108. It will thus be evident that when the cylinder 63 is reciprocated the drill rod 64 is simultaneously positively rotated.

Pivottally mounted upon the lower side of the head 105 is a projecting finger 109 having an actuating handle 110 adapted to be held in one or a plurality of positions as by a usual manually operable pin and slot connection 111 as clearly shown in Fig. 5. The plurality of notches shown are adapted to permit holding of the drill steel 64 at different elevations to facilitate any operation thereon which might be deemed necessary, such for instance, as removing or replacing the usual drill bit not shown. The finger 109 when operative is disposed within an annular recess 112 formed in the upper end of a chuck member 113 by which the drill rod 64 is carried, and the cylinder 63 may thus be reciprocated without reciprocating the drill rods. During such an operation the relative movement between the cylinder and piston merely serves to compress air in the ends of the cylinder which may if desired be supplied by suitable valve mechanism to the compartment 64^c for cleaning cuttings from a drilled hole. As this specific mechanism is clearly described and claimed in my copending application, Ser. No. 751,237, filed Nov. 21, 1924, further detailed description of the same is herein deemed unnecessary. It will thus be evident that the drill tube 64 may be held against reciprocation while it is independently rotated through the improved independent rotation means including the chain 101 heretofore described, driven from the crank shaft 55. It is to be noted that the drill rod may be rotated in opposite directions by means of the reverse bevels 46, 47 and the friction clutch 49, thus permitting the proper screwing or unscrewing of the drill bits or the drill rod sections.

It will herein be noted that the actuating gears for the shafts 48 and 83 are suitably housed within the dust tight hollow base casting 9 and that suitable collapsible dust bellows 114 and 115 surround the feed screw columns 14 and 15 and the transmission shafts, thus preventing access of dust or other foreign substance to the threads of the screws. It will further be noted that the feed nuts and the drill actuating mechanism are all enclosed within the dust tight casing 58.

In the operation of my improved drilling mechanism it will herein be noted that when

the mechanism has been transported under its own power to the desired location the operator manipulates the actuating lever 30, rotating the worm gear 20 and thus causing the guiding frame 7 to be swung upwardly about its pivot 8 into its operative drilling position as indicated clearly by dotted lines in Fig. 1, the lugs 12 on the base frame 9 being rigidly secured in any suitable manner to the I-beams 6, as by bolts, at that time. The desired reverse bevel is then operatively connected with the shaft 75 and the feed shaft 83 is consequently actuated, thus causing the feed nuts 88 and 94 to be rotated and the drill fed upwardly to the top of the guiding frame. The feed is then thrown out and the drill bit carrying rod is secured within the chuck 113 and the desired reverse bevel 73, 74 is then operatively connected to the drill actuating shaft 48 and the drill rod is consequently reciprocated in the desired manner. The feed nuts 88 and 94 are then again rotated in the required direction and the drill bit is fed downwardly at the desired drilling speed. During the drilling operation the drill rod is rotated continuously by means of my improved independent positive rotation mechanism. If it is desired to ream the hole, the finger 109 is inserted within the groove 112 in the chuck 113 and the rod is prevented from reciprocation, the drill being fed upwardly and downwardly in the hole as the drill rod rapidly rotates, thus performing a reaming function. When it is desired to again transport the drill to another working place the operator then swings the guiding frame downwardly in transport position, as indicated in full lines in Fig. 1, the feed screws 14 and 15 straddling the power unit 3 at this time, thus forming a very low and compact mechanism, it also being understood that the drill cylinder 63 and the supporting frame 58 are at the lower end of the guiding frame at that time to clear the power unit 3. It will also be noted that if it is desired to rotate the drill rod 64 in opposite directions the friction clutch 49 may be operated as desired and the desired reverse bevel 46, 47 may be connected to the actuating shaft 48.

As a result of my invention it will herein be noted that improved feeding and drill actuating connections are provided which may be operated irrespective of the angular position of the guiding frame relative to the truck frame. It will further be noted that improved drilling mechanism is provided which is of a comparatively compact and low structure which may be transported with facility and which may be adjusted into its operative drilling position expeditiously. It will still further be noted that all the actuating parts are enclosed within dust tight casings or bellows, thus preventing entrance of foreign matter to the moving parts and thereby increasing the life of the same.

These and other advantages of my invention will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A drilling mechanism comprising a truck including a power driving element, a guiding frame pivotally mounted thereon, drill bit reciprocating mechanism including a rotatable drive element slidably guided by said guiding frame, means for feeding said drill reciprocating mechanism relative to said guiding frame, and operative driving connections between said power driving element and said mechanism.

2. A drilling mechanism comprising a truck having a power driving element, a guiding frame pivotally connected to said truck, drill bit reciprocating mechanism including a rotatable drive element slidably guided by said frame, means for feeding said drill reciprocating mechanism relative to said guiding frame, and driving connections between said power driving element and said mechanism operative irrespective of the angular position of said frame relative to said truck.

3. A drilling mechanism comprising a truck including a power driving element, a guiding frame pivotally mounted thereon, drill bit reciprocating mechanism including a rotatable drive element slidably guided by said guiding frame, means for feeding said drill reciprocating mechanism relative to said guiding frame, and operative driving connections including a friction clutch between said power driving element and said mechanism.

4. A drilling mechanism comprising a truck including a power driving element, a guiding frame pivotally mounted thereon, mechanism including a rotatable drive element for percussively actuating and rotating a drill bit slidably guided by said guiding frame, means for feeding said drill actuating and rotating mechanism relative to said guiding frame, and operative driving connections including reversing mechanism between said power driving element and said actuating mechanism.

5. A drilling mechanism comprising a truck having a power driving element, a guiding frame pivotally mounted thereon, mechanism including a rotatable drive element for percussively actuating and rotating a drill bit slidably guided by said guiding frame, means for feeding said drill actuat-

ing and rotating mechanism relative to said guiding frame, and operative driving connections between said power driving element and said actuating mechanism including a driven element disposed concentrically with said frame pivot.

6. A drilling mechanism comprising a truck having a power driving element, a guiding frame pivotally connected to said truck, mechanism including a rotatable drive element for percussively actuating and rotating a drill bit slidably guided by said frame, means for feeding said drill actuating and rotating mechanism relative to said guiding frame, and driving connections between said power driving element and said actuating mechanism operative irrespective of the angular position of said frame relative to said truck, said driving connections including a driven element disposed concentrically with said frame pivot.

7. A drilling mechanism comprising a tractor having a power driving pulley, a guiding frame adjustably mounted on said tractor, mechanism including a rotatable drive element for percussively actuating a drill bit slidably guided by said frame, operative driving connections between said pulley and said actuating mechanism, and mechanism driven from said pulley for feeding said percussive mechanism relative to said guiding frame.

8. A drilling mechanism comprising a movable base having a power driving element thereon, a guiding frame pivotally mounted on said base, mechanism including a rotatable drive element for percussively actuating a drill bit slidably guided by said frame, means for feeding said drill actuating mechanism relative to said guiding frame, and operative driving connections between said power element and said actuating mechanism.

9. A drilling mechanism comprising a movable base having a power driving element thereon, a guiding frame pivotally mounted on said base, mechanism for percussively actuating a drill bit carried by said frame, means for feeding said actuating mechanism relative to said frame, and operative driving connections between said power driving element and said actuating mechanism and feeding means.

10. A drilling mechanism comprising a tractor having a power driving element, a guiding frame pivotally mounted on said tractor, mechanism for percussively actuating a drill bit carried by said frame, and means driven from said power driving element and including a rotatable member carried by said actuating mechanism for feeding the latter relative to said frame.

11. A drilling mechanism comprising a tractor having a power driving element, a guiding frame pivotally mounted on said

tractor, mechanism for percussively actuating a drill bit carried by said frame, and means driven from said power driving element and including a rotatable member carried by said actuating mechanism for feeding the latter relative to said frame irrespective of the angular position thereof relative to said tractor.

12. A drilling mechanism comprising a tractor having a power driving element, a guiding frame pivotally mounted on said tractor, drill bit actuating mechanism carried by said frame, and means including a stationary feed screw carried by said frame, and a cooperating feed nut carried by said actuating mechanism for feeding the latter relative to said frame.

13. A drilling mechanism comprising a tractor having a power driving element, a feeding frame pivotally mounted thereon and having a stationary feeding element, drill bit actuating mechanism carried by said frame and having a rotatable feeding element cooperating with said stationary element, and operative driving connections between said power element and said rotatable feeding element including a driven element disposed concentrically with said frame pivot.

14. A drilling mechanism comprising a tractor, a guiding frame pivotally mounted thereon, drill bit reciprocating and rotating mechanism carried thereby, means for feeding said mechanism relative to said frame, and means including reversible friction controlled gearing for driving said mechanism.

15. A drilling mechanism comprising a tractor having a power driving element, a guiding frame pivotally mounted thereon, mechanism for percussively actuating a drill bit carried by said frame, and means driven by said power driving element for feeding said actuating mechanism relative to said frame irrespective of the angular position thereof relative to said tractor.

16. A drilling mechanism comprising a movable base frame, a feeding frame pivotally mounted thereon, drill bit actuating mechanism carried by said feeding frame, and means for feeding said actuating mechanism relative to said feeding frame including a stationary feed screw carried by the latter.

17. A drilling mechanism comprising a movable base frame, a feeding frame pivotally mounted thereon, drill bit actuating mechanism carried by said feeding frame, and means for feeding said actuating mechanism relative to said feeding frame including a feed nut carried by said actuating mechanism.

18. A drilling mechanism comprising a movable base frame, a guiding frame carried thereby and angularly adjustable relative thereto, mechanism including a rotatable drive element for percussively actuating a

drill bit slidably guided by said guiding frame, means for feeding said drill actuating mechanism relative to said guiding frame, and means carried by said base frame for driving said actuating mechanism irrespective of the angular adjustment of said guiding frame with respect to said base frame.

19. A drilling mechanism comprising a movable base frame, a standard carried thereby, drill bit actuating mechanism carried by said standard, means for feeding said actuating mechanism relative to said standard including a transmission shaft disposed longitudinally of and journaled on the latter, and means for driving said actuating mechanism comprising a shaft disposed parallel with said feed shaft.

20. A drilling mechanism comprising a movable base frame, a standard pivotally mounted thereon, drill bit actuating mechanism carried by said standard, and means for feeding said actuating mechanism relative to said standard including a plurality of stationary feed screws carried by the latter.

21. A drilling mechanism comprising a movable base frame, a power driving element fixedly secured to said frame, a standard pivoted on said base frame, drill bit reciprocating mechanism slidably guided by said standard, means for feeding said drill reciprocating mechanism relative to said standard, means for adjusting said standard relative to said base frame, and operative driving connections between said power driving element and said reciprocating mechanism.

22. A drilling mechanism comprising a movable base, a standard thereon, drill bit reciprocating mechanism carried by said standard and including a rotatable shaft, positive rotation means operated independently of any reciprocating action of said mechanism for rotating the drill bit comprising a driving element disposed coaxially with and driven by said shaft, a driven element disposed coaxially with and operatively connected to the drill bit, and a cooperating flexible transmission element connecting said driving element with said driven element.

23. A drilling mechanism comprising a movable base, a standard mounted thereon, mechanism carried by said standard for reciprocating the drill bit including a rotatable shaft, means for positively continuously rotating the drill bit including means driven from said shaft, and means for locking the drill bit against reciprocation.

24. A drilling mechanism comprising a movable base, a standard thereon, mechanism carried by said standard for percussively actuating a drill bit and including a rotatable element, and continuous positive rotation means for the drill bit including connections distinct from said percussive mechanism comprising an element driven by

said rotatable element, and operative driving connections between said driven element and the drill bit.

25. A drilling mechanism comprising a movable base, a standard thereon, drill bit actuating mechanism carried by said standard comprising means for reciprocating the drill bit, a rotatable shaft, and positive rotation means for the drill bit operating independently of the reciprocating action of the latter and comprising a driving element disposed coaxially with and driven by said shaft, and connections between said driving element and the drill bit.
- 10 26. A drilling mechanism comprising a movable base, a standard thereon, drill bit actuating mechanism carried by said standard comprising means for reciprocating the drill bit including a rotatable shaft, and positive rotation means for the drill bit operating independently of the reciprocating action of the latter and comprising a driving element disposed coaxially with and driven by said shaft, a driven element also distinct 20 from said reciprocating means and disposed coaxially with and operatively connected to the drill bit, and driving connections between said driving element and said driven element.
- 25 27. A drilling mechanism comprising a movable base frame, a standard thereon, drill bit actuating mechanism carried by said standard, means for feeding said actuating mechanism relative to said standard including a stationary element, and collapsible housing means for said element.

- 30 28. A drilling mechanism comprising a standard, drill bit actuating mechanism carried by said standard, means for feeding said actuating mechanism relative to said standard including a feeding element, and collapsible housing means for said element disposed between said standard and a portion of said actuating mechanism.

- 40 29. A drilling apparatus comprising a base frame, mechanism carried thereby for positively reciprocating a drilling tool, means driven by an element of said reciprocating mechanism for causing continuous rotation of said drilling tool on its axis during reciprocation thereof, and means for interrupting reciprocation while permitting rotation of said drilling tool.

- 45 30. In a drilling apparatus, a portable base, a guiding standard mounted thereon, tool reciprocating mechanism slidably mounted on said standard, an engine on said base, rotating driving connections between said tool reciprocating mechanism and said engine, and mechanism driven directly from said rotating driving connections for rotating the tool.

- 50 31. In a drilling apparatus, a portable base, a guiding standard mounted thereon, 55 a tool reciprocating mechanism movable

longitudinally on said standard, an engine on said base, mechanism for feeding said tool reciprocating mechanism relative to said standard, driving connections between said engine and said tool reciprocating mechanism, and mechanism driven by said driving connections for rotating the tool.

In testimony whereof I affix my signature.

THORE R. E. RUNDQVIST.
